UNITED STATES PATENT OFFICE.

HARRY SLADE, OF WAKEFIELD, ENGLAND.

HEADER-JOINT FOR FUEL-ECONOMIZERS.

1,161,078.

Specification of Letters Patent.

Patented Nov. 23, 1915.

Application filed June 23, 1914. Serial No. 846,737.

To all whom it may concern:

Be it known that I, HARRY SLADE, a subject of the King of Great Britain, residing at Wakefield, Yorkshire, England, have invented certain new and useful Improvements in Header-Joints for Fuel-Economizers, of which the following is a full, clear, and exact description.

This invention relates to fuel economizers, particularly to the fastening of the tubes to the headers, and its object is to provide improved means for the purpose, whereby the apparatus is enabled to withstand higher pressures than have heretofore been considered practicable.

To this and other ends the invention consists in the novel features of construction and combinations of elements hereinafter described.

20 A convenient and effective form of the invention is illustrated in the accompanying drawing, in which—

Figure 1 is a central section taken longitudinally through one of the tubes and through the upper and lower headers, the section being taken through the shorter diameter of the lid which closes the hand hole in the top of the upper header, this hand hole being elliptical in shape as customary in constructions of this general kind. Fig. 2 is a side view of one of the locking rings provided to lock the tubes in place in the headers.

The tube A, preferably with a slight taper at the ends, is provided at its ends with circumferential grooves B, and the headers E, F are provided with correspondingly shaped openings for the ends of the tubes. On the inside the headers are formed with shoulders D around the openings mentioned. The upper header at proper intervals throughout its length is provided with elliptical shaped hand holes closed by removable lids—one of which is shown in section at X Fig. 1, the section being through the shorter diameter of the ellipse. The lid is applied to the hand hole from the inside of the header and its tapered periphery is drawn up into the hand hole against the correspondingly tapered wall of the same and there held by a bolt construction (not shown) well known and customarily used for the purpose. The slightly elliptical shape given to the hand hole is to permit the removal of the lid X, this being effected by drawing it down from the hole into the header, and giving it a quarter turn

to bring its shorter diameter parallel with the longer diameter of the hand hole, after which the lid can readily be taken out.

The parts having been assembled as shown in the drawing, with the grooved ends of the tubes projecting into the interior of the headers just beyond the shoulders D, the split locking rings C, of a thickness greater than the depth of the grooves B, are placed upon the inner beveled ends of the tube, and forced backward over the same until they spring into the grooves B, clasping or hugging closely the same with their portions which project beyond the grooves overhanging the header shoulders D, and constituting collars which effectively prevent the headers from being forced from the tubes, and resist any stresses tending to separate the parts.

75 The rings are made of metal, and are preferably sufficiently resilient to spring into the grooves and hug the same tightly, but they can be made, if desired, to have little or no resiliency. In any case they should have sufficient resistance to shearing stress to perform their functions properly.

With the tubes locked in place as described, the apparatus can be subjected to high internal pressures without danger of the headers being blown off the tubes. It will also be noted that the construction herein illustrated and described permits the split rings to be applied to the grooved ends of the tubes

90 after they and their headers have been assembled and fitted together, this operation taking place in the upper header through hand holes which are afterward closed, and in the lower header by inserting the ring by hand through one of the tube holes in 95 the lower header and then fitting it around the inwardly projecting grooved lower end of the tube which has been fitted into the next adjoining hole, and so on throughout the length of the header. This feature I believe to be new with me. A stronger and 100 surer connection between the tubes and headers is thereby obtained than would otherwise be practicable, while at the same time the split rings are so positioned that they may 105 be reached and manipulated from the inside of the header whenever it is desired to remove them for any purpose—as for example to permit the withdrawal of the tube with which they are associated. By removing the 110 appropriate lid X, the split ring upon the grooved inner end of any desired tube pro-

jecting into the interior of the upper header can be readily reached and manipulated; as also can the split ring on the grooved opposite end of the tube which projects into the interior of the lower header—there being used for this purpose, in practice, a tool consisting of a stout handle bar long enough to pass down from above through the tube into the lower header and having on its lower 10 end a pointed and upwardly turned hook by which the split ring can be engaged and pried out of its groove.

It is to be understood that the invention is not limited to the specific form illustrated, 15 but can be embodied in other forms without departure from its spirit. It can also be employed in other apparatus than fuel economizers.

What I claim is:

20 1. The combination of a header having a tube receiving opening, an annular shoulder on the interior of the header bordering the inner end of the opening, a tube having a

circumferentially grooved inner end which projects into the interior of the header beyond said opening and the annular shoulder bordering the inner end of the same, and a locking ring fitted in said groove and overhanging said shoulder. 25

2. The combination of a header having a 30 tapered tube receiving opening, an annular shoulder on the interior of the header bordering the inner end of the opening, a tapered-end tube fitting the said opening and having a circumferentially grooved portion 35 which projects into the interior of the header beyond said opening and the annular shoulder bordering the inner end of the same, and a split locking ring fitting in said groove and overhanging said shoulder. 40

In testimony whereof I affix my signature in the presence of two subscribing witnesses.

HARRY SLADE.
